 a corporation of Illinois

Application September 16, 1950, Serial No. 185,273

2 Claims. (Cl. 202—17)

1

This invention relates to methods and apparatus for recovering oil from oil shale.

Prior art methods for recovering oil from oil shale include initially disintegrating the shale and raising the disintegrated shale to an elevated temperature for volatilizing the oil. These prior art methods suffer from a serious disadvantage. It is somewhat difficult to disintegrate oil shale finely, especially when the shale is rich in oil, since the organic matter present in the shale tends to cause the comminuted shale particles to adhere or stick together. Particularly at elevated temperatures, oil shale tends to become more or less gummy with resultant adhesion of the oil shale particles at devolatilizing temperatures.

I have now provided method and apparatus for recovering the oil content of oil shale in which the shale is subjected to two successive disintegrating steps. Devolatilization is carried out concurrently with the second disintegrating step. Thereafter, the devolatilized shale and the volatile products are separated and the separated devolatilized shale particles are fluidized with a gas containing free oxygen at an elevated temperature for burning off the residual carbonaceous matter in the shale. The hot combustion gases then generated are utilized in carrying out the disintegrating and devolatilizing steps. As will be disclosed in greater detail hereinbelow, no difficulties are encountered in my process and apparatus due to sticking together of shale particles, and practically complete recovery of all the values present in the oil shale can be accomplished with a minimum number of steps.

It is therefore an important object of the present invention to provide method and apparatus for completely, conveniently and inexpensively recovering the oil content of oil shale.

Other and further objects and features of the present invention will become apparent from the following description and appended claims as illustrated by the accompanying drawings showing, by way of example, apparatus according to the present invention. More particularly:

Figure 1 is a side elevation, with parts shown in vertical section, of apparatus according to the present invention; and

Figure 2 is a cross sectional view taken along the line 2—2 of Figure 1.

Reference is made to the copending application of John I. Yellott, Serial No. 762,589, entitled "Comminution Device," filed July 22, 1947, and issued as Patent No. 2,515,541. This copending application discloses a combination, with

5 a flash pulverizing device for solid material capable of yielding an entrainment of comminuted solids in a streaming gas, of a vortex chamber arranged so as to receive said streaming entrainment in a generally tangential direction and at one side of the axis of said chamber, the latter being provided with a central axial discharge aperture. In this apparatus, granular solid material may be comminuted by a method described as follows. The flash pulverizing device includes a source of expansible fluid held under a pressure such that the fluid can be expanded with a pressure drop of at least 15 lbs. per sq. in. The compressed fluid is continuously discharged from this source into an elongated conduit, to form a stream of compressed fluid flowing at a velocity less than one-half of the critical velocity but, in any event, at least sufficient to suspend therein a granular solid permeable to the compressed fluid. There is thus established a stream of compressed fluid flowing in an elongated conduit and capable of being expanded with a pressure drop of at least 15 lbs. per sq. in. This stream of fluid is passed into a restricted area, 10 such as a convergent nozzle or a restricted orifice, so as practically instantaneously to accelerate said fluid to critical velocity and simultaneously to reduce the fluid pressure by at least 15 lbs. per sq. in. The fluid is discharged from the restricted area (the convergent nozzle or restricted orifice) as by allowing the fluid to escape into a divergent nozzle, into a conduit of at least the same diameter as the conduit upstream of the restricted area, or directly into the vortex chamber. Concurrently and continuously, solid granules are introduced into the flowing stream of compressed fluid sufficiently far upstream of the constricted area to suspend the solid granules in the flowing stream of compressed fluid and to 15 permit acceleration of said granules by said streaming fluid in said restricted area. The amount of solid material introduced into the streaming fluid is limited so as not to prevent a pressure drop, at the restricted area, of at least 15 lbs. per sq. in. In general, less than 10 parts and preferably not more than 4 parts (by weight) of solids should be used to each part of fluid. Then, on passing through and past the restricted area, the solid granules are shattered, probably 20 due to the sudden expansion of the compressed fluid contained within the granules which are permeable to the compressed fluid and are believed to have become permeated thereby while being contacted by the compressed fluid upstream 25 of the restricted area.

Reference is made to the patent Yellott 2,515,542 which discloses and claims this method of flash pulverizing.

Thus, the flash pulverizing device yields an entrainment of comminuted solid particles moving rapidly but under lower fluid pressure than the original entrainment of relatively coarse particles to be comminuted. The kinetic energy content of the entrainment of comminuted or shattered particles is utilized for further comminution in the vortex chamber. The entrainment of comminuted or shattered particles is discharged, from the flash pulverizing device, through a divergent nozzle, or through a short conduit (mentioned hereinabove), or, preferably, directly, into the vortex chamber. This discharge is directed generally tangentially into the vortex chamber, so that rapidly flowing entrainment initially impinges against the chamber wall and then establishes a vortical or whirling flow in said chamber, which is provided with an axial central discharge opening. Due to the vortical or whirling movement of the fluid, the relatively less fine shattered particles move radially outwardly within the vortex chamber, while the relatively fine particles tend to remain in the central region of the vortex chamber and are discharged through the central axial aperture. The relatively less fine particles thrown radially outward within the chamber by centrifugal force are carried around in the outer portion of the chamber and are there further comminuted by impact against the peripheral wall of the chamber and against other particles and by abrasion between said outer wall and other particles. When thus comminuted, disintegrated or worn down to smaller particle size, the resulting smaller particles are discharged through the axial central discharge aperture.

Thus, in the vortex chamber, the kinetic energy of the mixture of fluid and solids issuing from the constricted area in the flash pulverizing conduit is utilized for further comminution in the vortex chamber directly receiving said mixture, as by impact against the walls of the vortex chamber, by abrasion against the wall of the vortex chamber and by impact and/or abrasion between flash pulverized particles. Further, the vortex chamber tends to separate the variously sized solid particles and to pulverize additionally the coarser of those particles by impact and/or attrition.

The present invention relates to a combination, with a modified form of the method and apparatus of said Yellott application, of additional steps and apparatus elements. The resulting combinations form novel method and apparatus particularly adapted for the recovery of the oil content of oil shale, as will be discussed in greater detail hereinbelow.

According to the present invention, the temperature in the vortex chamber is maintained high enough to bring about conversion into volatizable form of the organic matter present in the shale and devolatilization of the shattered shale particles. This temperature may suitably range from 800° to 1500° F., and, preferably, from about 1000° to 1200° F. For maintaining the vortex temperature at the indicated value, a sufficient amount of hot fluid is injected tangentially into the vortex chamber. Both the fluid utilized in flash pulverizing the shale and the fluid injected into the vortex chamber are substantially devoid of free oxygen. Therefore, combustion will not take place within the vortex chamber. By suitable proportioning of the fluid

streams entering the apparatus and by adjusting their temperatures, the temperature within the vortex chamber can be accurately controlled.

Upstream of the vortex chamber, the temperature is maintained below the devolatilizing temperature of the shale and, specifically, below the temperature at which shale particles tend to adhere to each other or to the walls of the apparatus. Thus, the flash pulverizing nozzle will not become clogged and no other troubles due to development of gumminess are encountered.

The effect of the elevated temperature within the vortex chamber is not merely that of volatilizing oily shale constituents. Thus, mere raising of the temperature of the shale, particularly to within the devolatilization temperature, renders the shale more grindable and thus brings about a higher degree of comminution, all other factors being equal. Devolatilization also renders the shale more easily grindable. Further, rapid raising of the temperature of the flash pulverized shale particles to within the devolatilization temperature tends to generate vapor within the shale particles. Thus, if the evolution of vapor is sufficiently rapid, the shale particles may be shattered explosively by the evolution of vapor within the particles. Such explosive shattering of the shale particles by vapor rapidly liberated within the particles can be brought about at the beginning of the devolatilization, since the volatilization of only a relatively small part of the volatile content of the shale will suffice to bring about the results described.

In general, both greater disintegration and more extensive devolatilization in the vortex chamber are favored by more rapid movement of fluid and solids within the vortex chamber; by higher temperature in the vortex chamber, by longer residence in the vortex temperature; and by a high ratio of fluid to solids in the vortex chamber. More extensive devolatilization is favored by finer particle size, both of the shale introduced into the vortex chamber and of the particles further comminuted within the vortex chamber. It will thus be understood that since many factors favor both finer particle size and more extensive devolatilization, there will be a tendency for any variation in any one factor in a direction favoring finer subdivision to bring about a more extensive devolatilization at a rate that, at first glance, may seem disproportionate to the extent of the variation. Thus, when a temperature within the vortex chamber is raised to a relatively limited extent, the shale is rendered more easily grindable; more vapor is liberated, and liberated more rapidly, within the shale particles favoring explosive shattering by the liberated vapor and more vapor is evolved from the particles, thus adding to the fluid content of the vortex and increasing the rate of movement within the vortex. But, as a result of the finer subdivision then obtained, devolatilization will be more extensive which in turn leads to finer subdivision so that the initial relatively limited temperature raised in the vortex chamber may ultimately cause a rather significantly finer subdivision and more extensive devolatilization.

In brief, greater fineness and hence more extensive devolatilization are brought about by the action of a number of concurrently effective factors including easier grinding due to elevated temperature, shattering of particles by rapid generation of vapor within the particles, and increased rate of movement within the vortex due to liberation of additional vapor which also increases the

ratio of fluid to solids. Further, any one of these factors tends to accelerate the others so that the resulting changes may be said to be self-accelerating.

From the foregoing, it will be apparent that, according to my invention, fine subdivision and devolatilization of the shale can be effected in the vortex chamber within a relatively short time.

The preferred gas entering the flash pulverizing apparatus is super-heated steam which can easily be separated from the volatilized shale constituents. But, if desired, combustible or inert gases can also be injected into the flash pulverizing apparatus, for instance, producer gas. Steam or hot producer gas or preferably hot combustion gases can be injected into the vortex chamber.

A very important feature of the process step practiced within the vortex chamber is the fact that the shale particles, although within devolatilizing temperature, do not adhere or stick to each other or to the walls of the apparatus. There are several possible explanations for this fact. First, devolatilization proceeds very rapidly within the vortex chamber, due to the small particle size of the shale, and the intimate fluid particle contact, so that the gumminess of each particle persists for only a fraction of a second. Further, each particle is suspended in fluid and thereby spaced from other particles. Finally, the gummy shale particles are admixed with devolatilized and therefore no longer gummy particles.

The product obtained in the vortex chamber is a suspension, of finely divided devolatilized shale still containing some residual non-volatile carbonaceous matter, in a fluid made up of both the two streams entering the apparatus and of the volatile constituents of the shale.

Downstream of the vortex chamber, means are provided for separation of fluid and solid material from the hot suspension discharged from the vortex chamber. The separated fluid is directed to a condenser, where the fluid is separated into liquid and gaseous components. The more or less oily liquid then obtained is the principal desired final product.

The finely divided devolatilized shale (which contains residual non-volatile carbonaceous material) separated from the suspension issuing from the vortex chamber contains a considerable amount of heat. Both the carbon content and the heat content of this devolatilized shale are recovered by transferring the separated fine shale into a fluidizing chamber for traversal by an oxygen-containing gas such as air for combustion of the carbonaceous matter. The resulting combustion gases may be utilized directly for injection into the vortex chamber or may be utilized for generating and superheating steam which is then sent through the disintegrating and devolatilizing means.

In effect, the devolatilized shale is charged into the combustion apparatus in preheated condition. Due to this preheating and to the fine subdivision of the shale, complete combustion of the carbonaceous material in the shale can be effected in spite of the fact that the devolatilized shale contains relatively much more inorganic material than carbonaceous material. By other methods, complete combustion of the carbon content of the shale cannot easily be effected.

The completely spent hot shale discharged from the fluidizing chamber can be subjected to heat exchange with air in a second fluidizing chamber for preheating this air which is then employed in the fluidized combustion step. In

this manner, the heat content of the spent shale is recovered and the efficiency of the combustion step enhanced.

Apparatus for carrying out the above disclosed process is shown in the drawings. There, the numeral 10 indicates a hopper having a conical bottom for receiving coarsely fragmented shale. The hopper 10 is provided at its discharge end with a double bell and hopper device 11 or other gas-lock means for discharge into a tank 12 having a conical bottom 13 discharging into a conduit 14. The latter communicates directly with and serves to conduct the shale to be devolatilized into a horizontally extending tubularly enclosed screw feeder or conveyor 16, driven by a motor 17. The screw conveyor 16 moves the shale, by way of a vertical extension 16a, into a horizontally extending conduit 20. Steam, producer gas, combustion gas or other calorific gas or inert gas or mixtures of such gases under pressure or other fluid substantially devoid of free oxygen are admitted into the left hand end of the conduit 20 ahead of a valve 20a and into the upper portion of the tank 12 through a valved conduit 21 tapping the conduit 20. The right hand end portion of the conduit 20, downstream of the discharge opening of the screw conveyor 16, is constricted, as at 25, to form a convergent-divergent nozzle communicating directly and tangentially with a circular vortex chamber indicated generally by the reference numeral 30 and extending in a generally horizontal axial direction. More particularly, the vortex chamber 30 includes spaced disc-shaped left and right side walls 31 and 32, together with an intermediate cylindrical wall 33. The end of the nozzle 25 is attached to the cylindrical wall 33, preferably approximately midway between the side walls 31 and 32 so as to discharge into the chamber 30 transversely and to one side of the axis of the chamber 30.

A conduit 35 is adapted to discharge steam, combustion gas and producer gas or the like, hot fluid substantially devoid of free oxygen tangentially into the chamber 30. The conduit 35 may have its discharge orifice spaced from the discharge orifice 25 by 90°, 180°, 270°, or as otherwise desired.

The right hand side wall 32 of the chamber 30 is formed with a central axial aperture 36 discharging into a conduit 37, which may discharge into a cyclone type or other separating device 40 (for separating the comminuted devolatilized shale from its fluid suspension medium), the devolatilized shale being discharged through a conduit 41, and the fluid entraining medium being discharged through a conduit 42. The latter, in turn, discharges the fluid into a condenser 43 from which liquid and gaseous products may be recovered separately. If steam is injected into the apparatus, the liquid products will include water which can be separated from the liquid products by conventional methods.

The hot devolatilized shale moves through the conduit 41 into a receptacle 45 and from the latter through a valved conduit 46 into a riser 47 for a first fluidizing chamber 48. Air (from any suitable source) is admitted into the riser 47 to carry the shale into the fluidizing vessel 48 where the shale forms a fluidized bed which is maintained at combustion temperature for burning off the carbon content of the devolatilized shale. The spent or decarbonized shale overflows from the fluidizing vessel 48 through a conduit 49 discharging the shale into a riser 50 for a second fluidizing vessel 51. Air (from any suitable

source) is admitted into the riser 50 for carrying the spent shale up into the fluidizing vessel 50 where a heat exchange is effected between the spent shale and the air. After this heat exchange, the shale is discharged from the fluidizing vessel 51a through a conduit 52 and discarded.

The air preheated by traversing the fluidized spent shale in the chamber 51 leaves the latter through a conduit 52 discharging into the cyclone separator 53 where any shale entrained by the preheated air is separated and returned to the fluidizing vessel 51. After passing through the separator 53, the preheated air moves through a conduit 55 into the riser 47 and into the fluidizing vessel 48.

The combustion gases generated within the first fluidizing vessel 48 are discharged therefrom through a conduit 58, passed through a cyclone separator 59 for separating therefrom any entrained shale, which is returned to the fluidizing vessel 48 through a conduit 60. From the separator 59 the combustion gas passes into a conduit 62 which discharges into the conduit 35 through a valve 63. This valve is opened only when it is desired to inject the combustion gases directly into the vortex chamber 30. A valved conduit 65 branching off from the conduit 62 admits combustion gas to a steam generator and/or superheater 66, from which the combustion gases are discharged through a conduit 67. Water or steam is admitted to the steam generator and/or superheater 66 through a conduit 68. Steam generated and/or superheated in the element 66 is discharged therefrom through a conduit 69 having one valved branch 70 discharging into the conduit 20 and another valved branch 71 discharging into the conduit 35.

If desired, steam to be superheated may be conducted through a conduit 72, a coil 73 within the fluidizing vessel 48, and through a valved conduit 73 into the conduit 70 for discharge into the conduit 20.

At the start of the operation of the above described apparatus, shale in coarsely fragmented form is charged through the hopper 16 and the gas-lock 11 into the tank 12. More particularly, the shale should be capable of passing freely through the discharge orifice 25. The shale granules should have their maximum dimension not in excess of one third of the orifice diameter. Steam, combustion gas, producer gas or other calorific gas or inert gas or mixtures of these fluids, under pressure, are introduced through the conduits 20 and 21 into the tank 12 and caused to flow through the conduit 20. The screw conveyor 16 is operated to advance the shale to be disintegrated and devolatilized into the stream of fluid flowing through the conduit 20. The nozzle 25 is so spaced from the discharge opening of the screw conveyor 16 that the shale discharged into the conduit 20 will be accelerated to the point of entrainment by the fluid flowing through the conduit 20 before reaching the nozzle 25. Instantaneous expansion occurs continuously and uninterruptedly as the compressed fluid in the conduit 20 passes through the nozzle 25 and causes shattering of the shale particles, apparently by virtue of the expansion of the compressed fluid contained within the porosities of the shale.

The operating pressure of the fluid in the conduit 20 should be at least 15 pounds per square inch and may be as high as 750 pounds per square inch or higher. At the preferred operating

gauge pressure of about 200 pounds per square inch in the conduit 20, as when the fluid is superheated steam as from 350° to 450°, the pressure downstream of the nozzle 25 may suitably be less than 60 pounds per square inch, for instance, 5 pounds per square inch or less.

It should be understood that the pressure drop across the nozzle 25 should be such as to accelerate the fluid flowing through the nozzle to the critical velocity. Ahead of the nozzle 25, the fluid may suitably flow at from 10 to 400 ft. per second. The pressure upstream of the nozzle should be at least 15 pounds per square inch above the pressure downstream of the nozzle. The extent of comminution in the nozzle is determined, inter alia, by the pressure level of operation, by the difference between the upstream and the downstream pressures on the two sides of the nozzle 25, by the ratio of fluid to solids passing through the nozzle 25, and by the rate of movement of solids through the nozzle 25. Finer comminution is effected in the nozzle by the maintenance of maximum upstream and minimum downstream pressure, by the use of relatively large amounts of fluid as compared to the amount of solids, and by the establishment of rapid flow of solids through the nozzle.

The streaming entrainment of comminuted shale issues from the nozzle 25 into the vortex chamber 30 where the fluid forms an inwardly spiraling vortex. The fluid being introduced flows at a high rotative speed but at a low inward speed in said vortex so that the relatively less fine particles, under the action of centrifugal force, are kept in the peripheral portions of the vortex chamber 30 where they are further comminuted or disintegrated, by the initial impact upon the chamber wall, by further impact upon the chamber wall (subsequent to the initial impact following discharge from the nozzle 25), by impact upon other particles or by attrition. Because of the high rotative rate of movement in the fluid and its relatively low inward rate of movement, there is a strong tendency to return to the outer portion of the vortex for further grinding action, such relatively less fine particles as may be thrown or bound into, or otherwise may reach the inner portion of the vortex chamber. The relatively fine particles introduced through the nozzle 25, as well as the particles of similar fineness resulting from further grinding of relatively less fine particles, are entrained by the fluid being discharged through the axial aperture 36 and are carried through the conduit 37 to the separator 40 for recovery through the conduit 41.

The extent of comminution in the vortex chamber 30 is determined, inter alia, by the temperature of the fluid discharged into the vortex chamber (as will be discussed in more detail herein below), the rate of movement of the solid particles within the vortex chamber, the ratio of fluid to solids, and the like. Finer comminution may be effected by rapid movement of solids and the use of large amounts of fluid as compared with the amount of solids introduced into the vortex chamber. Fluid tangentially admitted into the vortex chamber 30 through the conduit 35 contributes to the vortical movement of solid particles through the vortex chamber 30.

Fluids are admitted into the system at two localities. First, the fluid required for flash pulverization is admitted into the conduit 20 and there admixed with the shale. Additional amounts of fluid are admitted tangentially into

the vortex chamber 30 through a conduit 35, under such pressure, at such velocity or with such momentum as may be required to overcome the internal pressure within the vortex chamber and, if desired, to increase the rate of flow within the vortex chamber. The preferred compositions and the temperatures of the fluids admitted at these two localities are discussed in the following paragraphs.

The temperature of the fluid flowing through the conduit 20 should be such that no clogging of the nozzle 25 will take place. This end will be attained if the temperature of the fluid admitted into the conduit 20 is kept below 600° F. and, preferably, not higher than 500° F. The exact maximum permissible temperature at the nozzle 25 and in the conduit 20 is determined by the temperature at which the shale turns sticky or gummy, which varies according to the origin of the shale. The temperature in the vortex chamber 30 is maintained, as disclosed hereinabove at a level where the shale will be devolatilized, for instance, at from 800° to 1500° F. and, preferably, from about 1000° to 1200° F.

As disclosed hereinabove, more complete devolatilization in the vortex chamber is favored, *inter alia*, by small particle size of the solid material, high temperature, long time of residence of the solid material in the vortex chamber, the introduction of large amounts of fluid into the vortex chamber, and the like. I, therefore, adjust the conditions to bring about small particle size, high temperature, long time of residence and/or introduction of relatively large amounts of fluid, so as to bring about complete devolatilization of the shale.

The heat required for maintaining the indicated temperature in the vortex chamber is derived, as disclosed hereinabove, from the combustion of the devolatilized shale in fluidized condition. For this purpose, the shale discharged from the vortex chamber should preferably be characterized by a particle size not greater than 10 mesh and not less than 200 mesh. As also disclosed hereinabove, the heat of combustion may be utilized directly by injecting the combustion gases into the vortex chamber 30 through the conduit 62, the valve 63 and the conduit 35. A second method of utilizing the heat content of the combustion gases involves the generation of superheated steam in the element 66. The resulting superheated steam may be utilized both for flash pulverization and for maintaining the desired temperature in the vortex chamber, passing for these purposes through the conduit 69 and the conduit 70 into the conduit 20 and through the conduit 71 into the vortex chamber. If desired, superheated steam may be utilized only for flash pulverization while a part of the combustion gases are injected directly into the vortex chamber. Ordinarily sufficient air is admitted into the first fluidizing chamber for combustion of the carbon content of the devolatilized shale substantially to carbon dioxide.

Many details of composition, structure and procedure may be varied within a wide range without departing from the principles of this invention and it is therefore not my purpose to limit the patent granted on this invention otherwise than necessitated by the appended claims.

I claim:

1. The method of recovering oil from coarsely fragmented oil shale which comprises providing a source of hot fluid substantially devoid of free oxygen and capable of being expanded with a pressure drop of at least 15 lbs. per square inch; continuously and uninterruptedly discharging said fluid from said source while confining the

pressure drop of at least 15 lbs. per square inch; continuously and uninterruptedly discharging said fluid from said source while confining the discharged fluid so that the discharged confined fluid will flow at a substantially uniform velocity less than the critical velocity and with a pressure drop less than the critical pressure drop; thereafter continuously and uninterruptedly flowing said discharged fluid through a sharply restricted area so as suddenly to accelerate said fluid to critical velocity by instantaneously reducing the fluid pressure by at least 15 lbs. per square inch; concurrently, continuously and uninterruptedly introducing said shale, in the form of granules capable of freely passing through said restricted area, into said flowing confined fluid upstream of said restricted area; controlling the flow of said confined fluid from the point of introduction of said shale to said restricted area so that said shale will be entrained by said fluid; adjusting the amount of shale introduced into said fluid to a value less than 10 parts by weight for each part of fluid; said shale granules being subjected while entrained to the first acceleration to critical velocity of said fluid as said fluid flows from said source to and through said restricted area whereby said granules are shattered and there is formed a rapidly flowing suspension of shattered particles in expanded fluid; said shale up to this point being maintained at an elevated temperature below the temperature at which said shale particles tend to adhere together; confining said suspension within a cylindrical axially limited space while forming said suspension into a vortex, the rate of flow in said vortex being such that shattered particles are kept circulating within said space and thereby further comminuted; incorporating with said vortex additional fluid formed as combustion gas during the combustion step recited hereinbelow and substantially devoid of free oxygen and sufficiently hot to maintain the temperature in said vortex at a point where said shale will be devolatilized; withdrawing from the center of said vortex hot fluid having suspended therein relatively fine particles of devolatilized shale; separating said devolatilized shale from said hot fluid; condensing the oily fraction of said fluid to recover the oil content of said shale; and forming the separated devolatilized hot shale into a fluidized bed and burning off the carbon content of said shale by flowing through said bed a gas preheated as recited hereinbelow and containing free oxygen; and forming the decarbonized shale into a fluidized bed by flowing a gas containing free oxygen through said bed of decarbonized shale whereby said gas is preheated.

2. The method of recovering oil from coarsely fragmented oil shale which comprises providing a source of hot fluid substantially devoid of free oxygen and capable of being expanded with a pressure drop of at least 15 lbs. per square inch; continuously and uninterruptedly discharging said fluid from said source while confining the discharged fluid so that the discharged confined fluid will flow at a substantially uniform velocity less than the critical velocity and with a pressure drop less than the critical pressure drop; thereafter continuously and uninterruptedly flowing said discharged fluid through a sharply restricted area so as suddenly to accelerate said fluid to critical velocity by instantaneously reducing the fluid pressure by at least 15 lbs. per square inch; concurrently, continuously and uninterruptedly introducing said shale, in the form of granules

11

capable of freely passing through said restricted area, into said flowing confined fluid upstream of said restricted area; controlling the flow of said confined fluid from the point of introduction of said shale to said restricted area so that said shale will be entrained by said fluid; adjusting the amount of shale introduced into said fluid to a value less than 10 parts by weight for each part of fluid; said shale granules being subjected while entrained to the first acceleration to critical velocity of said fluid as said fluid flows from said source to and through said restricted area whereby said granules are shattered and there is formed a rapidly flowing suspension of shattered particles in expanded fluid; said shale up to this point being maintained at an elevated temperature below the temperature at which said shale particles tend to adhere together; confining said suspension within a cylindrical axially limited space while forming said suspension into a vortex, 15 the rate of flow in said vortex being such that shattered particles are kept circulating within said space and thereby further comminuted; incorporating with said vortex additional fluid substantially devoid of free oxygen and sufficiently hot to maintain the temperature in said vortex at a point where said shale will be devolatilized; withdrawing from the center of said vortex hot fluid having suspended therein relatively fine

5

10

particles of devolatilized shale; separating said devolatilized shale from said hot fluid, condensing the oily fraction of said fluid to recover the oil content of said shale; forming the separated devolatilized hot shale into a fluidized bed and burning off the carbon content of said shale by flowing through said bed a gas preheated as recited hereinbelow and containing free oxygen; and forming the decarbonized shale into a fluidized bed by flowing a gas containing free oxygen through said bed of decarbonized shale whereby said gas is preheated; said hot fluid and said hot gas introduced into the vortex chamber containing heat derived from said combustion.
